UNITED STATES PATENT OFFICE.

CLAYTON A. DUNHAM, OF GLENCOE, ILLINOIS, ASSIGNOR TO DUNHAMETER CORPORATION, OF CHICAGO, ILLINOIS.

DESIGN FOR AN AUTOMOBILE STEP PLATE.

Application filed December 17, 1924. Serial No. 11,723. Term of patent 3½ years.

To all whom it may concern:

Be it known that I, CLAYTON A. DUNHAM, a citizen of the United States, residing at Glencoe, in the county of Cook and State of Illinois, have invented a new, original, and ornamental Design for Automobile Step Plate, of which the following is the specification, reference being had to the accompanying drawing, forming part thereof, in which:

Fig. 1 is a perspective view of the step-plate in position on the running board of an automobile.

Fig. 2 is a plan view of the step-plate.

Fig. 3 is a side view of the step-plate.

I claim:

The ornamental design for an automobile step plate, as shown.

December 5th, 1924.

CLAYTON A. DUNHAM.
